UNITED STATES PATENT OFFICE.

GUSTAVE L. HERZ, OF NEW YORK, N. Y.

ANTIVIBRATION DEVICE.

No. 853,548.

Specification of Letters Patent.

Patented May 14, 1907.

Application filed January 15, 1907. Serial No. 352,369.

To all whom it may concern:

Be it known that I, GUSTAVE L. HERZ, a subject of the Crown of Austria, and a resident of the borough of Brooklyn, in the city and State of New York, have invented a new and useful Antivibration Device, of which the following is a specification.

The object of my invention is to provide a device for use in connection with vehicles whereby the vehicle spring may be permitted to be compressed under one degree of friction and permitted to expand under another degree of friction thereby preventing undue vibration of the vehicle body when the vehicle wheels are subjected to severe jolts.

A further object is to provide certain improvements in the construction, form and arrangement of the several parts whereby a device may be constructed which will be very simple in construction, positive in action and not liable to become disarranged under the severe usage to which such devices are subjected.

A practical embodiment of my invention is represented in the accompanying drawings, in which

Figure 1 represents my improved anti-vibration device in side elevation, so much of a vehicle body frame, axle and spring being shown as will give a clear understanding of the location of the device with respect to the same, Fig. 2 is an enlarged top plan view of the device, Fig. 3 is a transverse central section through the device on an enlarged scale, Fig. 4 is a side view of the device, Fig. 5 is a side view with certain of the parts removed, and Fig. 6 is a detail section of the lost motion connection between the body and axle.

A hollow casing of cylindrical form is denoted by 1 and it is provided with a centrally arranged hollow axle 2 and a removable cover 3.

A wheel 4 has its hub 5 mounted on the axle 2, which hub is provided on its end 6 exterior to the cover 3 of the casing with an arm 7, the free end of which is connected to the axle 8 as follows:—A cylinder 9 is provided with a lug 10 for the purpose of hinging the cylinder to the free end of the arm 7 by means of a pivot bolt 11. This cylinder 9 is provided with a screw cap 12. A rod 13 is hinged at 14 to a bracket 15 fixed to the axle 8 in the present instance by being clipped thereto on top of the spring 16. The upper end of this rod 13 extends through the cap 12 of the cylinder 9 and is provided with a head

17 fitted to slide in the bore of the said cylinder. Upper and lower cushions 18, 19, are located within the cylinder 9 in position to engage the head 17 of the rod 13 after it has moved a slight distance in either direction, which cushions may be made of rubber or other suitable material. A lost motion connection is thus made between the arm 7 of the wheel 5 and the axle 8. This wheel 5 is held in position on the axle 2 by providing an annular interior shoulder 20 in the hub 5 and reducing the end of the axle 2, as shown at 21. A retaining plate 22 is held in position overlapping the shoulder 20 by means of a screw 23.

The arm 7 is clamped against movement on the extension 6 of the hub 5 by providing a bolt 24 having a screw threaded engagement with the bore of the extension 6, a washer 25 being interposed between the head of the bolt 24 and the outer face of the arm 7.

A second wheel 26 is mounted concentric to the wheel 4 and is arranged to be clutched thereto when the wheel 4 is moved in one direction and released therefrom when the wheel 4 is moved in the opposite direction, the means for obtaining this result being herein shown as the well known roller clutch, the wheel 4 forming the inner member and the wheel 26 forming the outer member of the clutch, rollers 27 being interposed between the two members for clutching and releasing them.

A band brake 28 surrounds the wheel 4 and is supported by the casing 1 at a point intermediate its ends by a screw bolt 29 which engages a boss 30 on the said brake. The free ends of the brake 28 are independently adjusted toward each other for regulating the amount of friction on the periphery of the wheel 4 by means of set screws 31, 32, having lock nuts 33, 34, which set screws pass through a lug 35 on the exterior of the casing 1. A band brake 36 is similarly provided for the friction wheel 26, the said band brake being supported by the casing 1 intermediate its ends by means of a screw bolt 37 which engages a boss 38 on the said band brake. The ends of this band brake 36 are forced toward each other independently by means of adjusting bolts 39, 40, and lock nuts 41, 42, the said bolts being mounted in the lug 35 of the casing 1.

The casing 1 is held stationary on the body 43 of the vehicle at any desired position.

In operation, as the spring is compressed

under the impulse of a sudden jolt, the first part of the compression of the spring is unretarded owing to the lost motion in the connection between the arm 7 and the axle 8. 5 The further compression of the spring is retarded with the desired amount of friction under the influence of the band brakes 28 and 36 which exert their retarding influence on the peripheries of the wheels 4 and 26 10 which are locked together by the clutch rollers 27. As the parts tend to return to their normal position, a less amount of retarding friction is imposed upon the spring 16 for the reason that the brake 28 only is 15 utilized for exerting its retarding friction on the wheel 4, the wheel 26 being released from the wheel 4 by the clutch rollers 27. It will be seen that any desired amount of friction can be applied between the band brakes 20 28, 36, and their respective friction wheels 4, 26, so as to obtain the required result. It will, furthermore, be seen that any slight jars on the traction wheels of the vehicle will be unimpeded owing to the lost motion in 25 the connection between the arm 7 and the axle 8 of the vehicle.

What I claim is:—

1. The combination with a vehicle spring, of means for retarding the compression and 30 expansion of the spring comprising two parts arranged to be clutched to and released from each other and band brakes engaging said parts.

2. The combination with a vehicle spring, 35 of means for retarding the compression and expansion of the spring comprising two parts arranged to be clutched to and released from each other, band brakes engaging said parts and means for adjusting the frictional engagement of said brakes with said parts.

3. The combination with a vehicle spring, 40 of means for retarding the compression of the spring with one degree of friction and the expansion of the spring with another degree of friction comprising two parts arranged to be clutched to and released from each other and band brakes engaging said parts.

4. The combination with a vehicle spring, 45 of means for retarding the compression of the spring with one degree of friction and the

expansion of the spring with another degree of friction comprising two parts arranged to be clutched to and released from each other, band brakes engaging said parts and means 55 for adjusting the frictional engagement of said brakes with said parts.

5. The combination with a vehicle spring, of means for retarding the compression and expansion of the spring comprising a support, 60 two parts concentrically mounted thereon, a roller clutch interposed between the parts and band brakes engaging said parts.

6. An anti-vibration device comprising a 65 casing, two wheels rotatably mounted therein, a roller clutch interposed between said wheels and band brakes carried by said casing arranged to frictionally engage the peripheries of said wheels. 70

7. An anti-vibration device comprising a casing, two wheels rotatably mounted therein, a roller clutch interposed between said wheels, band brakes carried by the casing for frictionally engaging the peripheries of said 75 wheels and means for adjusting the frictional engagement of said brakes with said wheels.

8. An anti-vibration device comprising a hollow casing, its axle, a wheel mounted on 80 said axle, a second wheel mounted concentric with the first named wheel, a roller clutch interposed between the two wheels and band brakes carried by the casing for engaging the peripheries of said wheels.

9. An anti-vibration device comprising a 85 hollow casing, its axle, a wheel mounted thereon, a second wheel mounted concentrically with the first-named wheel, a roller clutch, interposed between the two wheels, band brakes carried by the casing in position 90 to frictionally engage the peripheries of said wheels and means for adjusting the frictional engagement of said brakes with said wheels.

In testimony, that I claim the foregoing as my invention, I have signed my name in 95 presence of two witnesses, this 2nd day of January 1907.

GUSTAVE L. HERZ.
